BRAIDING MACHINE

John A. Muller, Passaic, N. J., assignor to United States Rubber Company, New York, N. Y., a corporation of New Jersey

Application March 18, 1939, Serial No. 262,682

5 Claims. (Cl. 96—3)

This invention relates to braiding machines and more particularly to machines for producing woven braids or sheaths, about work being fed therethrough.

5 Most braiding machines can be divided into three general classes; the first class comprising machines which produce braids composed of two layers of individual strands running in helical paths in opposite directions progressively about 10 and along the work, the second class comprising machines which produce braids composed of individual strands extending in adjacent parallel interlacing helical paths paralleling the work and forming a sheath thereabout, and the third 15 class comprising machines which produce braids composed of two sets of individual strands extending in opposite interlacing helical paths about the work to form "basket" or "maypole" type woven sheaths thereabout.

20 The braiding machines of my invention fall into the last of these classes of braiding machines and serve to produce "basket" or "maypole" type braids about the work passing through the machines.

25 Conventional braiding machines of the third general class mentioned above have not been found satisfactory as many objections and difficulties have been encountered therein. Such machines employed flat circular guide plates in 30 which were formed two similar, endless, sinuous, intersecting guideways extending in a generally circular direction about a common braiding center at the center of the machine. The work upon which the braid was to be formed passed through 35 the center of the plate and two sets of spaced spool carriers were arranged to travel in opposite directions along these guideways and about the work during operation of the machines. Each spool carrier extended perpendicularly from the 40 flat face of the guide plate and a strand of braiding material extended from a spool on the carrier to the free end of the carrier and from the free end of the carrier inwardly to the center of braiding at the center of the machine. This arrangement placed an eccentric load upon each of the 45 spool carriers and a binding between each carrier and its guideway which required extra operating power at all times while the machine was running.

50 This arrangement also caused the length of the strands between the free ends of the carriers and the braiding center to vary greatly as the carriers operated in and out along their sinuous paths to and from the innermost and outermost 55 parts thereof. A heavy and complicated slack-

absorbing mechanism was necessary upon each carrier to care for the loose length of strand thus caused in order to maintain a more or less uniform tension therein at all times during operation of the machine. When the proper tension 5 was not maintained during the braiding operation, twisting, kinking, and breaking of the strands was liable to result. These slack-absorbing mechanisms were expensive to make and maintain, increased the loading on the spool 10 carriers and the amount of power needed for operating the machine, materially decreased the size of spools that could be accommodated by the carriers and required extra power for overcoming the resistance offered by the heavy springs carried by each slack-absorbing device. While 15 braiding machines of this class operated fairly well for some braiding purposes, with more specialized types of braiding, such as where wire or other relatively heavy or stiff materials were 20 used, these machines failed materially to give satisfactory results and failed to produce the uniformly braided sheaths desired.

The braiding machine of my invention has largely eliminated these and other objectionable 25 features of the earlier braiding machines of this class by providing two or more braiding-heads and a work conveyor coupled with a source of power. Each braiding head comprises a cylindrical housing encircling and supporting a composite guide plate which is in the form of a zone or a portion of a hollow sphere or spheroid and by providing in this composite plate two similar, 30 endless, sinuous, intersecting guideways extending generally circumferentially therealong. Two 35 sets of equally spaced spool carriers are positioned within this hollow plate and are arranged to travel in opposite directions in the guideways therein. Each carrier extends inwardly and normally from the spherical or spheroidal surface of 40 the composite plate at all times regardless of its particular location therein and accordingly directly toward the geometric center of the sphere or spheroid containing the plate. The center of the sphere or spheroid is also the braiding center for the braiding head and the work upon which the sheath is to be formed extends through this central point and perpendicularly to the generally circumferential paths of the 45 guideways.

50 Thus during braiding operations the spool carriers are always at a constant distance from the braiding center and the free length of strand therebetween always remains constant. The carriers oscillate back and forth as they travel along 55

their respective endless guideways but the distance from an individual carrier to the braiding center does not vary. Only the amount of material necessary for forming the sheath or braid 5 is drawn from the spools on the carriers and accordingly no slack has to be absorbed. No heavy slack-absorbing mechanisms are necessary for the strands of braiding material used in my machine. While a tension control device is used 10 upon each carrier in my invention this is only for the purpose of supplying the desired tension to the individual strands according to the particular braiding material being used by the head and the degree of binding desired by the sheath upon 15 the work. Because the spool carrier and strand therefrom both extend in a straight line toward the braiding center no eccentric loading is placed upon the carrier and accordingly no extra drag has to be overcome when the machine operates.

20 An endless train of power transmitting gears extends around the composite guide plate and is positioned between the plate and the outer cylindrical housing. This train is coupled with a source of power and serves to propel the spool 25 carriers along the guideways during the operation of the braiding head. The outer housing forms a protective casing for this train of gears and also forms the main supporting structure for the entire assembly.

30 The compactness of each braiding head enables two or more to be placed in close proximity and in line, so that they may be operated together to form a plurality of sheaths upon the work at one time. These braiding heads are 35 coupled to change speed gearing and a source of power so that they may be operated in synchronism or at relatively different speeds when desired.

An endless work conveyor is also coupled to 40 the source of power by means of interchangeable gears, so that various speeds may be produced therein which are relative to the braiding speed of the braiding head or heads. This conveyor supports and carries the work passing 45 through the braiding head or heads and normally its speed is the same as the lineal braiding speed of the braiding head or heads so that uniformly close and tight sheath or sheaths are formed upon the work. However, said interchangeable gears are provided so that the conveyor speed may be increased and the conveyor made to pull the work through the head and thereby increase the lay angle of the strand and produce a more openly braided sheath when de- 50 sired.

This invention will be more readily understood from the following description taken in conjunction with the accompanying drawings, in which:

Fig. 1 is a side elevational view of my invention 60 showing a braiding machine comprising two braiding heads and a belt conveyor coupled to a source of power; one of the braiding heads being broken away along substantially the vertical longitudinal central plane thereof;

Fig. 2 is a transverse elevational view of one 65 of the braiding heads taken substantially along the section line 2—2 of Fig. 1, but having a tape reel and support therefor removed;

Fig. 3 is a transverse sectional view of a portion 70 of my braiding head taken substantially along the section line 3—3 of Fig. 1;

Fig. 4 is a partial development of the sinuous guideway and carrier structure shown in Fig. 3 75 as viewed from within the braiding head;

Fig. 5 is an elevational view of one of the spool carriers used in my braiding head;

Fig. 6 is a side elevational view of the spool carrier, partly in section, taken substantially along section line 6—6 of Fig. 5;

Fig. 7 is a diagrammatical view showing the extreme lateral positions reached by the spool carriers and individual strands during braiding at the true braiding center of the head;

Fig. 8 is a diagrammatical view, somewhat similar to Fig. 7, but showing how individual strands may be extended around a work guide for special braiding operations of the head; and

Fig. 9 is a modified form of composite guide plate which may be used in my invention.

The braiding machine of a preferred embodiment of my invention is shown in Fig. 1 and employs a main frame generally indicated by the numeral 1. This frame is arranged to support two longitudinally spaced braiding units or braiding heads 2 and 3, a source of power 4, and one end of an endless belt conveyor 5. The two braiding heads and the belt conveyor are connected to the source of power so that the relative speeds of braiding of the heads and the lineal speed of the conveyor may be varied relative to each other. The braiding heads 2 and 3 are similar and accordingly details of construction and arrangement hereinafter described may be taken to apply equally to either unit. The two heads are shown together for the purpose of illustrating how a double braid or sheath and an intermediate separating cover may be placed upon the work at one time.

The braiding heads 2 and 3 are supported upon brackets 6 rigidly attached to the main frame 1 which serve to space and firmly position the braiding heads thereabove for clearance purposes. These brackets are rigidly attached to outer casings or cylindrical housings 7 of the braiding units 2 and 3. Each cylindrical housing 7 is of relatively heavy construction and serves to support and position the assembled parts of the braiding head.

A plurality of studs 8 are evenly spaced circumferentially about the housing 7, are fixedly secured therein, and extend inwardly toward the braiding center of the unit. Guide plates 9 and 10 are rigidly attached to this cylindrical housing 7 by means of connecting bolts 11. These guide plates are in the form of zones or portions of a sphere or spheroid whose geometric center is also the braiding center 12 of the head. Carried by the inner ends of the studs 8, in fixed relation therewith, are guide segments 13 which are rigidly keyed thereto as shown in Fig. 4 by the numeral 14. These guide segments are in the form of plates shaped as portions of the sphere or spheroid which includes the inner surfaces of the guide plates 9 and 10. Sinuous intersecting or interlacing paths or guideways 15 and 16 are formed between the guide plates 9 and 10 and the intermediately located segments 13 when assembled to guide the two similar sets of spool carriers 17 and 18. Thus it will be seen that all points along the guideways 15 and 16 are equidistant from the braiding center 12 regardless of the sinuous characteristics of the guideways so formed. The guide plates 9 and 10 and the guide segments 13 combine to form a composite guide plate which is in the shape of a central ring portion or zone of a sphere or spheroid. The spool carriers 17 and 18 referred to above will be more completely hereinafter described.

These inwardly extending studs 8 are rigidly secured in place in the cylindrical housing 7, in any desired manner, and mounted upon each stud 8 between the housing 7 and the guide segment 13 is an anti-friction bearing 19 clamped in place therebetween by the nut 21. Carried by this bearing 19 is a rotatable hub 22 upon which are mounted by bolts 23 an angular notched gear 24 and an angular toothed gear 26 so that both gears rotate freely about the stud 8. The circumferentially spaced studs 8, bearings 19 and hubs 22 locate the gears 26 so that an endless intermeshing gear train is formed about the assembled plates 9 and 10 and segments 13. A driven gear 27 is bolted to the bottom face of the angular gear 26 located upon the stud 8 at the bottom and center of the braiding head and is arranged to derive power from a driving gear 28 to actuate all of the gears 26 of the gear train in unison and thereby actuate notched gears 24. The notched gears 24 in turn propel the two sets of spool carriers 17 and 18 in opposite directions along the sinuous pathways 15 and 16, respectively, as indicated by arrows A and B, Fig. 4, while the head is in operation. Each notched gear 24 is provided with a pair of diametrically spaced peripheral notches 29 for receiving lugs or fingers 30 projecting outwardly from the base portions of the carriers 17. Each gear 24 is also provided with a second pair of diametrically spaced peripheral notches 31, intermediate the notches 29, for receiving the lugs or fingers 32 projecting from the base portions of the carriers 18.

Thus it will be seen that these carriers 17 and 18, moving in their respective guideways 15 and 16, travel along a surface which is a zone or portion of a sphere or spheroid whose center is the braiding center of the braiding head indicated by the numeral 12, Fig. 1. The free lengths of the strands 33 between the carriers 17 and 18 and the braiding center 12 always remain substantially constant regardless of the positions of the carriers during operation. The carriers oscillate laterally back and forth as they move along the guideways 15 and 16 during operation of the unit but only the amount of braiding material required for forming the sheath is pulled from the spools thereon during this operation; as distinguished from the alternate tensioning and slack that would exist if there were a variable distance between each carrier and the braiding center.

A work guide 34 has been found desirable in actual practice and is shown in Fig. 1 located near the central transverse plane of the head which is also the plane containing the circumferentially spaced studs 8. This work guide insures braiding of the sheath at substantially the geometric center of the composite plate structure formed of guide plates 9 and 10 and guide segments 13. The work guide 34 is securely but adjustably and replaceably held in place by struts 35 attached to the forward edge of the plate 9.

The source of power 4 is composed of a driving motor 36 of conventional design and a change speed gear structure generally indicated by the numeral 37 for operating shafts 38 and 39 for the braiding heads 2 and 3, respectively. This gear structure is such that the shafts 38 and 39 may be operated at the same speed or at different relative speeds as the particular braid being formed may require. The power shafts 38 and 39 are supported in place beneath the units 2 and 3 by bearings 40 and are arranged to drive the gears 28. Also coupled to the shaft 38 is a flexible coupling 41 which is provided with circumferentially spaced holes 42 for the insertion of a lever 43 so that the head 2 may be turned by hand when it is desired to install, adjust or replace movable parts thereof. A similar hand operating means may be employed for the braiding head 3 for a similar purpose, if desired.

An additional shaft 44 extends from the coupling 41 to a worm gear 45 for operating the conveyor 5. The worm gear 45 meshes with a pinion gear 46 mounted upon a shaft 47. Also mounted upon the shaft 47 and a shaft 48 are a pair of gears 49 and 50, respectively, which may be replaced by another pair of similar gears but of different ratio when it is desired to change the relative operating speed of the conveyor 5. An endless conveyor belt 51 is arranged to run upon the sprockets 52, one of which is keyed to the shaft 48 for driving purposes. The remote end of the conveyor (not shown) is also provided with a similar sprocket for supporting the endless belt in place.

A tensioning device is used in conjunction with my conveyor 5 for properly adjusting the tension of the conveyor belt 51. The belt passes over an idler sprocket 53 of the device which may be moved by screw means 54 to adjust the tension thereof. The top run of the conveyor belt 51 is positioned so that the work 55 being fed through the head 2, in the direction of the arrow C, rests upon the belt and may be fastened thereto, if desired, and conveyed or pulled thereby depending upon the lay angle desired in the braid being produced by the head.

As shown in Fig. 7 the braiding head may be operated without a work guide by synchronizing the speed of braiding of the unit with the speed of travel of the work passing therethrough so that the braiding center 56 remains at the center of the head and the length of the individual strand is always the same; even in the extreme lateral positions as indicated by numerals 57 and 58. However, in practice the work guide 34 (Fig. 1) is generally used and helps to insure the proper operation of the unit under all conditions.

It may be seen from Fig. 8 that when a work guide 59 is used the speed of the work 55 passing through the head may be made greater than the speed of braiding of the head which will draw the strands 60 around the work guide 59 and increase the lay angle thereof and will draw the center of braiding 61 away from the center of the unit and thereby produce a sheath having a somewhat open mesh. Dotted lines 62 indicate how the strands and braiding center may be pulled laterally to increase the lay angle and produce an exceptionally open braid or sheath when desired by merely increasing somewhat more the lineal speed of the work. Braiding conditions can thus be controlled by the speed at which the conveyor with the work moves relative to the speed of the braiding head. It will be seen that under all such conditions of operation a substantially uniform length of strand passes from the carrier around the work guide and to the point of braiding regardless of the distance the braiding point may be pulled to one side of the center of the unit. Since the conveyor and braiding heads are geared together their predetermined relative speeds do not vary during operation of the units and accordingly

a very uniformly braided sheath may be produced.

All of the spool carriers used in my braiding head are similar in construction to the spool carrier 17 shown in detail in Figs. 5 and 6. The carrier 17 has a base portion 70 composed of two circular flanges 71 and 72 which are interconnected by a bridge bar or guide bar 73. Projecting from the bottom of the flange 72 is a lug or finger 32, previously referred to. The bridge bar 73 is in the form of a thin but relatively wide and rigid connecting member between the flanges 71 and 72, is arranged to travel in the guideway 15, and is narrowed at its opposite ends to fit or accommodate the curvature of the guideway as indicated at 14 (Fig. 4). The flanges 71 and 72 are provided with faces 75 and 76 which are bevelled to engage the opposite faces of the guide plates 9 and 10 and the guide segments 13. The portions 77 and 78 of the flanges 71 and 72, between bevelled edges 75 and 76, are undercut to prevent binding between these flanges and parts of the plates 9, 10 and segments 13.

25 An upstanding inverted U-shaped frame 80 is rigidly carried upon the flange 71 of the carrier 17 and is arranged to support a spool 81 for braiding material and a tension control device generally indicated by the numeral 82. The 30 spool 81 is rotatably retained in place in the U-shaped frame 80 by a removable pin 83 which is arranged to fit in apertures 84 and 85 in said frame. A swinging lock bar 86 is attached to one side of the frame 80 and is provided with a 35 notched portion 87 which straddles a narrowed portion of the pin 83 and serves to retain the pin in place during operation of the carrier. A spring 88 serves to bias this lock bar and prevent accidental displacement of the pin 83.

40 The constant tension control device 82 is composed of a swinging bell-crank lever 89 having at its free end a brake shoe 90 arranged to engage the peripheral surface of the strand 33 of flexible material wound upon the spool 81 and 45 thus tends to hold the spool against rotational movement until a predetermined pull is exerted upon the strand 33. The opposite end of the bell-crank lever 89 is pivoted upon a bar 91 carried in the U-shaped frame 80 and an intermediate portion of the lever is provided with a connecting pin 92 to which guide rods 93 are pivotally attached. The free ends of the guide rods 93 fit into apertures 94 in the bite portion of the U-shaped frame 80 and springs 95 fit 50 around these rods and bear against the bite portion and thereby tend to force the bell-crank lever 89, and accordingly the brake shoe 90, into engagement with the peripheral portion of the strand of flexible material wound upon the spool 81. A limiting rod 96 is provided across the frame 80 beneath the intermediate portion of the bell-crank lever 89 and merely serves as a 55 stop member to limit the inward movement of the lever 89 when the spool 81 has been removed from the structure.

Also located in the bite portion of the U-shaped frame 80 is a replaceable guide eye 97 through which the strand 33 of flexible material passes when being drawn from the spool on the 60 carrier to the point of braiding of the head. The guide eye 97 is keyed or otherwise retained in place in the U-shaped frame 80.

Dotted lines are shown in Fig. 6 to indicate a position that may be assumed by the tension control device 82 when a comparatively full spool

of flexible material is being used upon the carrier. The arrangement of the parts of the control device is such that the braking action thereof places a substantially uniform tension upon the strand 33 being unreeled and fed from the carrier 17 at all times regardless of the amount of material wound upon the spool.

I have shown in Fig. 1 a support 98 carried upon the housing 1 and arranged to locate a roll of tape 99 directly over the work 55 being passed through the head. Carried by this support is a spring pressed tensioning roller arm 100 for holding the tape in place against the work. When it is desired to separate individual layers of braid being placed upon the work by separate 15 braiding heads, the tape from the roll may be fed beneath the second layer as it is being formed about the work. The spring pressed roller arm 100 tends to hold this tape in a smooth condition and the braiding action of the second 20 sheath automatically wraps the tape around the work while the braiding operation continues.

Fig. 9 of the drawings shows a modified form of a composite guide plate that may be used as a part of my invention. This composite guide 25 plate is in the form of a zone or portion of a sphere or spheroid and comprises guide plates 101 and 102 and guide segments 103 so positioned that two endless, sinuous, intersecting guideways 104 and 105 are formed therebetween 30 for carriers 17 and 18. This composite guide plate is similar to the guide plates 9 and 10 and 35 guide segments 13 of my preferred embodiment shown in Fig. 1, except that it is located at one side of the central plane of the sphere or spheroid instead of symmetrically of the central plane thereof, as is the case in my preferred embodiment. However, it should be noted that this composite guide plate could be formed of any portion or zone of a sphere or spheroid and 40 when so formed all portions of the guideways therein would be substantially equidistant from the geometric center thereof. Accordingly strands of braiding material which extend from the carriers upon the inner face of such a composite guide plate would always be at a constant 45 distance from the braiding center thereof and only the amount of material necessary to form the braid would be drawn from the spools thereon.

When it is desired to place my braiding head 2 in operation the carriers 17 and 18 are provided with spools 81 of flexible material and the strands 33 thereof are brought to a common 50 braiding center 12 which is the spherical or 55 spheroidal center of the guide plates 9 and 10 and segments 13 and are anchored to the work 55. As the source of power 4 starts to rotate the power shaft 38, the gears 27 and 28 are consequently rotated. Since the gear 27 is fixedly 60 secured to the bottom angular toothed gear 26 its rotation actuates all of the intermeshing angular toothed gear 26 of the gear train positioned circumferentially about the guide plates 9 and 10 and guide segments 13 and within the 65 cylindrical casing 7 of the unit. The rotation of the successive gears 26 are in opposite directions. Each gear 26 of the train of gears will in turn rotate its respective notched gear 24 in unison therewith. Notched portions 29 and 31 70 of each notched gear 24 will engage the extending lugs or fingers 30 and 32 upon the bases of the carriers 17 and 18 and thereby propel same about their respective guideways 15 and 16. The carriers 17 and 18 move in opposite directions 75

and cross each others paths as they proceed along the guideways. When the individual carrier 17, or 18, (Fig. 4) has been moved along the guideway to the central transverse plane of the head 2 by the notched portion 29 or 31 engaging the lug 31 or 32 the associated notched gear continues to rotate while the carrier disengages therefrom and continues in the direction of its guideway. At the time of this disengagement the notched portions 29 or 31 of the next successive notched gear moves into engagement with the projecting lug or finger 30 or 32 and thereby continues to actuate the carrier along its sinuous path.

15 It will be seen that such an arrangement, moving every other carrier in one direction and the remaining carriers in the opposite direction, causes the carriers to successively cross each others paths and thereby produce a braiding action of the well known "basket" or "maypole" type. During operation the distance between each carrier and the center of braiding of the head remains constant and since the braking action or resistance offered by the tension control device also remains constant, a constant tension is always maintained upon each individual strand helping to form the braid. No complicated slack-absorbing mechanism is required for the strands being fed from the carrier to the work. The tension control devices are required only for giving the correct tension to the strands according to the material being used to form the braid. This uniform tension placed in each individual strand is such that a uniformly close and tight braid may be formed by each braiding head of my invention. The braid may be formed as tightly as desired about the work and this may be directly controlled by the tension control devices located upon the individual carriers of the head.

40 The pull on each strand is always in a direct line with the carrier and thus no eccentric loading of the carrier, such as would cause binding in the parts thereof, is created and only a minimum of power for operating purposes is required.

45 The control of the relative speeds of two braiding heads 2 and 3 and the conveyor enables me to place uniformly braided sheaths of like characteristics upon the work at one time regardless of the difference in size of the individual superimposed sheaths and enables me at the same time to control the lay angle of each sheath.

50 Although the invention has been disclosed in connection with the specific details of preferred embodiments thereof, it must be understood that such details are not intended to be limitative to the invention except insofar as is set forth in the accompanying claims.

Having thus described my invention, what I claim and desire to protect by Letters Patent is:

55 1. A braiding head comprising a composite guide plate comprising a plurality of guide elements so shaped and positioned as to form a zone of a spheroid and a pair of endless, sinuous, intersecting guideways therebetween, and supporting means for said guide elements arranged to securely retain said elements in position in said braiding head, said supporting means comprising a load carrying housing encircling said guide plate and a plurality of spaced studs extending inwardly from the inner surface thereof, portions of said housing being relatively spaced outwardly of said guide plate whereby an endless enclosed circumferential gear chamber is formed therebetween.

60 2. A braiding machine comprising guiding plates having two endless, sinuous, intersecting guideways formed therein and having all portions thereof equidistantly spaced from a common center, sets of spool carriers positioned in said guideways and arranged to operate in opposite directions therealong, an endless series of intermeshing gears located outwardly of and adjacent said guide plates and operatively associated with the spool carriers for propelling the carriers of both sets simultaneously, and a generally circular load carrying frame positioned outwardly of said plates and gears and having means for securing said plates in relatively fixed relation, said frame and said guide plates jointly forming an endless enclosure for said gears and adjacent portions of said spool carriers.

65 3. A braiding machine comprising a load carrying main frame of substantially circular shape in transverse cross section and provided with continuous inwardly directed flanged portions at its opposite open ends, a composite guide plate having the shape of a zone of a spheroid positioned within the main frame, said guide plate having two endless sinuous intersecting guideways so formed in said plate as to divide the plate into two end sections and a plurality of intermediate sections, each end section having a flanged portion engageable with one of the flanged portions of the main frame, a plurality of relatively fixed studs extending radially from the inner surface of said main frame, and adapted to removably secure said intermediate sections in fixed position, sets of spool carriers positioned in said guideways, and power transmitting gears mounted upon said studs between said intermediate sections and the main frame and operatively associated with said sets of spool carriers for propelling said sets in opposite directions along said guideways, said main frame and said composite guide plate together forming an endless enclosure for said transmission gears and adjacent portions of said spool carriers.

70 4. A braiding machine comprising a hollow rigid annular supporting frame having the inner wall portion thereof conforming substantially to the shape of a section of a sphere, said inner wall portion being divided into two annular end sections and a plurality of intermediate segments spaced therefrom so as to define therebetween a pair of endless sinuous intersecting guideways having all parts thereof equidistantly spaced from a common braiding center, two sets of spool carriers positioned in said guideways and arranged to travel in opposite directions therealong, a plurality of inwardly extending studs secured to the outer wall portion of said frame and supporting at their inner free ends said segments in fixed positions relative to said end sections, and a set of operatively interconnected actuating gears for said spool carriers rotatably mounted upon said studs between the inner and outer wall portions of said frame.

75 5. A braiding machine comprising a rigid unitary annular housing having inwardly extending flanges formed at the opposite open ends thereof, a plurality of uniformly spaced studs projecting radially from the inner surface of the housing, a pair of flanged annular guide plates positioned within the housing and having the flanges thereof detachably secured to the inwardly extending flanges of said housing, a series of guide segments secured to the free ends of said studs and positioned between said guide plates so as to form therewith and with said housing an end-

less enclosed gear compartment, the adjacent edge portions of said plates and said segments being spaced relative to each other and being equidistantly spaced from a common braiding center so as to define a pair of endless sinuous intersecting guideways, a plurality of intermeshing gears located within said compartment and

rotatably mounted upon said studs, and a set of spool carriers operatively associated with said gears and arranged to travel along said guideways, said spool carriers at all times during operation of said machine remaining a constant 5 distance from said braiding center.

JOHN A. MULLER.
